STAKE FENCE

Albert M. Carlson, Chino, Calif.

Application October 29, 1956, Serial No. 43,564

Term of patent 14 years

(Cl. D28—1)

I claim:

The ornamental design for a stake fence, as shown.
